(57) **CLAIM**

We claim the ornamental design for a luminaire, as shown and described.

DESCRIPTION

FIG. 1 is a perspective view of a luminaire.

FIG. 2 is a front view of the luminaire shown in FIG. 1.

FIG. 3 is a rear view of the luminaire shown in FIG. 1.

FIG. 4 is a right side view of the luminaire shown in FIG. 1.

FIG. 5 is a left side view of the luminaire shown in FIG. 1.

FIG. 6 is a top view of the luminaire shown in FIG. 1.

FIG. 7 is a bottom view of the luminaire shown in FIG. 1.

FIG. 8 is a perspective view of a luminaire.

FIG. 9 is a front view of the luminaire shown in FIG. 8.

FIG. 10 is a rear view of the luminaire shown in FIG. 8.

FIG. 11 is a right side view of the luminaire shown in FIG. 8.

FIG. 12 is a left side view of the luminaire shown in FIG. 8.

FIG. 13 is a top view of the luminaire shown in FIG. 8.

FIG. 14 is a bottom view of the luminaire shown in FIG. 8.

FIG. 15 is a perspective view of a luminaire.

FIG. 16 is a front view of the luminaire shown in FIG. 15.

FIG. 17 is a rear view of the luminaire shown in FIG. 15.

FIG. 18 is a right side view of the luminaire shown in FIG. 15.

FIG. 19 is a left side view of the luminaire shown in FIG. 15.

FIG. 20 is a top view of the luminaire shown in FIG. 15; and,

FIG. 21 is a bottom view of the luminaire shown in FIG. 15.

The ceiling mount and suspension elements are shown in broken lines in the drawings to depict portions of the lighting fixture that form no part of the claimed design.

1 Claim, 15 Drawing Sheets
